INVENTOR

John T. Hay.
BY
Charles B. Montthrop
ATTORNEY.

UNITED STATES PATENT OFFICE.

JOHN T. HAY, OF LACKAWANNA, NEW YORK.

INNERSOLE, ARCH-SUPPORT, SHOE-CUSHION, AND VENTILATOR.

1,317,161.

Specification of Letters Patent. Patented Sept. 30, 1919.

Application filed October 11, 1917. Serial No. 196,047.

To all whom it may concern:

Be it known that I, JOHN T. HAY, a citizen of the United States, and a resident of the city of Lackawanna, in the county of Erie and State of New York, have invented a new and Improved Innersole, Arch-Support, Shoe-Cushion, and Ventilator, of which the following is a specification.

10 My invention relates to an insertion to be placed within boots and shoes, and is adapted to form a ventilated inner sole, a cushion heel, means for supporting the arch of the foot and ventilating the shoe.

15 The object of my invention is to provide an attachment for shoes which will furnish ventilation for the interior of the shoe, as well as the sole of the foot, support the arch of the foot at all points, and provide a resilient cushion for the foot.

20 A further object of my invention is to provide a combined insole, arch and cushion heel which when in use in shoes will keep the foot cool and comfortable and also prevent the foot from perspiring.

25 Other objects and advantages will be apparent as the nature of my invention is hereinafter set forth.

In the accompanying drawings, Figure 1 is a longitudinal section through a shoe and 30 through my device on the line A, A of Fig. 2, looking in the direction of the arrows. Fig. 2 is a plan view of the sole of a shoe and my device. Fig. 3 is a perspective view 35 of the under side of the heel portion of my device.

Similar numerals refer to similar parts throughout the several views.

Referring to these numerals, 1 is the usual 40 form of shoe upper attached to the sole 2 in the ordinary manner. 3 is an opening in the sole of the shoe in its arch portion and preferably toward the inner edge of the sole. 4 is a thimble inserted in opening 3 and having a collar 5 to one edge of which is movably attached the cover 6, which has a projection in the center thereof, so that the opening in the thimble 4 may be closed at will. The upper edge of the thimble 4, after being inserted through the opening 3, is riveted over to hold the thimble firmly in the sole.

50 7 is the ordinary heel of a shoe attached in the usual manner.

55 8 is an inner sole composed of two thicknesses of material and having a sole portion 9, an instep or arch portion 10, and a heel

portion 11. The upper thickness 12 of inner sole 8 is provided with ventilating holes 13, 13, etc. The under thickness of inner sole 8 is provided with channels or grooves 14, 14, etc., which register with ventilating holes 13, 13, etc., for supplying air to the inside of the shoe through opening 3 in the sole of a shoe. The arch portion 10 is provided with a lip extended upward, as shown, 60 to support the inner part of the arch of the foot. 15 is a steel spring riveted to the inner sole 8 to give strength to the arch portion 10. 16 is hollow rubber tube fastened to the heel portion 11 of inner sole 8 by 70 rivets 17, 17 and strip 18 and rivets 19, 19. Tube 16 is attached, as shown, around the edge of heel portion 11 and is made to assume the shape of a horseshoe.

Tube 16 raises the heel portion 11 and the 75 arch portion 10 from the sole of the shoe, so that when my device is in use in a shoe, the placing of the foot on the ground compresses tube 16 and the air is forced along the channels 14, 14, etc., and through the 80 ventilating holes 13, 13, etc. Arch portion 10 covers opening 3 in the sole, thus preventing the air from escaping through opening 3 until the foot is raised and the pressure removed. Tube 16 is then allowed to assume its normal position, thereby raising 85 arch portion 10 and heel portion 11 and creating a suction of air from outside the shoe through opening 3.

Tube 16 also acts as a heel cushion and 90 similar tubes may be attached in any manner desired to the sole portion 9 and arch portion 10 of the inner sole 8 for the purpose of providing a cushion sole for the foot of the wearer.

95 My device is designed so that it may be easily placed in a shoe or removed therefrom as the occasion may require.

It is apparent that changes in the form and structure of my invention, as shown, 100 may be made without departing from the spirit thereof.

Having thus described my invention, what I claim and desire to secure by Letters Patent is:

105 1. In a device of the character described, the combination with a shoe having a circular opening in the shank thereof, and a circular cover pivoted at the edge of said opening, of an inner sole composed of two 110 thicknesses of material, the upper thickness provided with a plurality of ventilating

holes, the lower thickness having branching channels in the sole portion thereof extending lengthwise of said sole in such a manner that said ventilating holes are directly over portions of said channels as well as at the termination of the same, the heel portion of said lower thickness having holes to register with the ventilating holes in the heel portion of said upper thickness, a metal strip attached to the under side of said innersole so as to strengthen the arch portion of said innersole and a resilient tube fastened to the under side of the heel portion of the innersole and around the edge thereof.

2. A removable innersole for shoes, composed of two thicknesses of material, the upper thickness provided with a plurality of ventilating holes, the lower thickness having branching channels in the sole portion thereof, extending lengthwise of said sole in such a manner that said ventilating holes are directly over portions of said channels, as well as over the ends of said channels, the heel and a part of the shank portions of said lower thickness having holes of the same size and to register with the ventilating holes in the heel and a part of the shank portion of said upper thickness, a metal piece attached to the underside of said innersole to strengthen the arch portion of said innersole and a resilient tube fastened to the

edge of the underside of the heel portion of the said innersole to form a cushion and an air circulating medium.

3. In a device of the character described, the combination of a shoe, having an opening in the shank thereof, a cover pivoted at the edge of said opening, the center of said cover having a projection to move said cover in or out of register with said opening, an inner sole composed of two thicknesses of material, the upper thickness provided with a plurality of ventilating holes, the lower thickness having branching channels in the sole portion thereof, one of which is directly over said opening, and which extends lengthwise of said sole in such a manner that said ventilating holes are directly over portions of said channels, and at the termination thereof, the heel portion of said lower thickness having holes to register with the ventilating holes in the upper thickness, a metal strip attached to, and for the purpose of strengthening the arch portion of said inner sole, and a resilient tube fastened to the underside of the heel portion of the inner sole, and around the edge thereof.
